INVENTOR:
James R. Speer.

United States Patent Office.

JAMES R. SPEER, OF PITTSBURG, PENNSYLVANIA.

Letters Patent No. 71,338, dated November 26, 1867.

IMPROVEMENT IN COTTON-BALE TIE.

The Schedule referred to in these Letters Patent and making part of the same.

TO ALL WHOM IT MAY CONCERN:

Be it known that I, JAMES R. SPEER, of Pittsburgh, in the county of Allegheny, and State of Pennsylvania, have invented a new and useful Improvement in Metallic Bands for Baling Cotton; and I do hereby declare that the following is a full and exact description thereof, reference being had to the accompanying drawings, and to the letters or reference marked thereon.

The nature of my invention consists in providing a clasp with apertures which are contracted, so as to grasp more firmly metallic bands and prevent them from unhooking or becoming otherwise disengaged while shipping, manipulating on shipboard, or otherwise handling the cotton-bales, it being an improvement upon the clasp described in my patent reissued.

My invention further consists in the use of semi-oval iron, when used in combination with said clasp for metallic bands for baling cotton.

My invention also consists in use of metallic bands when made in sections, and so arranged and adjusted with relation to the baling of cotton on the plantation, and the re-baling or compressing of the bales at the shipping ports, that one or more of the sections of the metallic bands may readily be removed and again used at the plantation for baling.

To enable others skilled in the art to make and use my invention, I will proceed to describe its construction and operation. In the accompanying drawings, which form part of my specification—

Figure 1 represents a top view of my improvement in metallic bands for baling cotton.

Figure 2 represents a longitudinal section of the same.

Figure 3 represents one mode of forming the short sections of the bands.

Figure 4 represents a top view of the clasp used in connection with the semi-oval iron.

Figure 5 represents a transverse section of the band made of semi-oval iron.

In the drawings, A represents the clasp, which is provided with contracted apertures marked 1 and 2, the form of said apertures being clearly shown in fig. 4. The clasp A is bent across the apertures, as shown in fig. 2, for the purpose of presenting an easy means for the hooking of the ends of the bands to the clasp. B represents the short section of the band, and is provided with hooked ends marked 3 and 4. C represents the long section of the band, one end of which is secured to the clasp, and the other end of which is provided with a hook, 5.

The operation of my improvement is as follows: The band C is arranged in the press in the ordinary manner, and the cotton compressed in the usual way. The short section B of the band is then hooked to the band C, as indicated at 4 and 5 of figs. 1 and 2; and then the hook 3 is hooked in the opening 1 of the clasp A, which completes the operation of securing the band on the cotton-bale at the plantation. When the bale is compressed at the shipping port the short section B of the band is removed and the hook 5 of the band C is hooked in the opening 1 of the clasp A. This will complete the operation of re-baling or compressing the cotton-bales at the seaports or other shipping points or ports.

The advantage of my improvement consists in making bands in sections for cotton-bales, thereby facilitating the re-baling process, for, as it is observed that in re-baling for the purpose of transportation, the bands are cut and adapted in length to the size of the compressed bales, and that portion of the band which is cut off is always lost to the planter. My improvement saves this part of the band, for the short sections can be returned to the planter and again used for baling at the plantation, thus saving to the planter, by the use of the short sections B, of the bands, about twenty-five per cent. in the cost of bands, and much time, labor, and trouble, in the process of baling and the re-baling of the cotton.

The use of semi-oval iron is another very important part of my invention, and has many advantages over the thin, flat bands, (hoop-iron.) The semi-oval iron is stronger and less liable to become twisted and out-of-shape, and presents less surface to the action of the atmosphere and other causes of oxidation. Another very great advantage obtained by the use of semi-oval iron, is its cheapness when compared with the cost of thin band-iron. The semi-oval iron costs less, and can, after it has served its purpose for baling cotton, be used for

making wrought nails, bucket-bails, pot and tea-kettles, &c., while the thin band-iron is unfit for other uses after it has been used for baling cotton.

Contracting one side of the openings of the clasp A will cause the band to be held firmly, and will prevent it from becoming unhooked or otherwise disconnected while handling and manipulating the bales; and bending the clasp across the aperture will present an easy and ready means for the insertion of the ends of the bands.

Having thus described the nature, construction, and operation of my improvement, what I claim as of my invention, is—

1. A clasp for baling cotton, said clasp being provided with contracted apertures of the form herein described, and bent in the manner and for the purpose set forth.
2. In combination with the above, I claim bands made of semi-oval iron and in detached sections, as herein described and for the purpose set forth.

JAMES R. SPEER.
